SHEET GRIPPING AND PULLING TOOL

Filed Oct. 19, 1944

UNITED STATES PATENT OFFICE

2,460,007

SHEET GRIPPING AND PULLING TOOL

Victor H. Hasselquist, Akron, Ohio, assignor to
The B. F. Goodrich Company, New York, N. Y.,
a corporation of New York

Application October 19, 1944, Serial No. 559,393

2 Claims. (Cl. 81—44)

1

This invention relates to tools for gripping and pulling sheet material and is especially useful in stretching ice-removing and other coverings about the surfaces of aircraft.

Objects of the invention are to provide for a sure grip on the margin of a covering without injury to the covering, to provide for a convenient handle on the covering for manual stretching of the covering, to provide lever means for amplifying manual effort, and to provide quick attachment and detachment.

These and other objects will appear from the following description and the accompanying drawings.

Of the drawings:

Fig. 1 is a perspective view of an airplane showing an ice-removing covering partially applied thereto and showing a tool constructed in accordance with and embodying the invention in position to stretch a portion of the covering.

Fig. 2 is a side elevation of the tool shown partially in section and in gripping position, a part of the covering being also shown.

Fig. 3 is a view to a larger scale of the operating nose of the tool shown in its released position, the view being in longitudinal vertical section.

Fig. 4 is a perspective view of a toggle member.

Fig. 5 is a perspective view of a modification of the invention in use in applying a covering.

Referring to the drawings, the tool is formed with a tubular hollow L-shaped housing having a relatively long operating portion 10 and a relatively short handle or grip portion 11. The operating portion has an open end which is partially closed by a block 12 and is notched therebelow, as at 13, to receive the margin of the covering 14. The notch 13 terminates in shoulders 13a providing a locating surface for the edge of the covering. The block 12 serves to provide a guide to the covering entering the notch and to this end has a curved surface 15 inclined toward the notch.

For providing positive grip of the covering, while at the same time avoiding injury thereto, the lower wall of the housing extends beyond the notch to provide a fixed jaw 16. A moveable jaw 17 of spring material is secured to the housing as by screws 18 at a position remote from the fixed jaw and normally stands away from the fixed jaw. For moving the moveable jaw toward the fixed jaw, a handle lever 20 is pivotally secured to the housing as at 21 near the elbow of the housing and extends through a clearance opening 22 therethrough along the handle portion 11. A link 23 is pivotally secured to the lever, as

at 24 and extends through the hollow operating portion of the housing. The link is formed with notches 25, 26 in the upper and lower faces or near its outer end for receiving a pair of toggle links 21, 27a in the form of and acting as moving struts. A notch 28 is formed in the housing to fulcrum the link 21 and a notch 29 is formed in the moveable jaw 17 to fulcrum the link 23. The block 12 acts as a stop to limit movement of the link 23 in the outward direction beyond a dead center position while the handle portion 11 of the housing limits movement of the lever 20 and thereby the link 23 in the opposite direction. The arrangement is such that when the lever 20 is pushed away from the handle portion, the links 27, 27a assume the inclined position of Fig. 3 and the moveable jaw 17 springs away from the fixed jaw 16 to release the covering, and when the lever 20 is moved toward the handle portion 11, the links 27, 27a are moved substantially to a perpendicular position, as in Fig. 2, with the strong action of moving struts, and move the moveable jaws 17 toward the fixed jaw with great force. Due to the high pressure developed by the toggle movement, the jaws may be smooth and of great area to avoid injury to the covering while nevertheless providing a strong grip on the covering.

The covering 14 is usually provided with a thickened margin 30 reinforced by a bead core 31. Where this is the case, the moveable jaw 17 of the tool is formed with a rib 32 to engage beyond the thickened margin 30 and securely lock the covering to the tool. In the locking position, the toggle links 21, 27a are substantially at a dead center position so that the covering is securely retained even when the handle 20 is released.

In use where a covering 14 is to be stretched about the surface of an airfoil to align apertures 14a in the covering with apertured hollow internally threaded rivets 35 secured to the airfoil, the tool is held with its fixed jaw adjacent the surface of the airfoil, the handle lever 20 is pushed away from the handle portion 11, and the notch of the housing is advanced over the margin of the covering until the locating surfaces 13a touch the edge of the covering. The handle lever 20 is then pushed toward the handle portion 11, straightening the toggle and gripping the margin of the covering. The covering may then be stretched, by pulling on the handle portion, to a position where screws may be entered into the hollow rivets through the apertures 14a of the covering. By proceeding progressively along the margin of the covering with successive pulling operations,

the covering may be progressively secured to the airfoil.

In the modification of the invention shown in Fig. 5, the tool is of the same construction as that previously described and in addition is provided on the operating portion of the housing thereof with a laterally extending fulcrum member 40. In the use of this tool, pins or studs 41 are inserted in the apertures of the hollow rivets on the airfoil and the elastic covering is stretched progressively over the airfoil into alignment with the pins and its apertures passed thereover to secure it in stretched condition. In effecting step by step stretching the fulcrum arm 40 is held against a pin laterally adjacent to the gripped portion and the tool is swung about such pin as a fulcrum to assist in the pulling action as shown in the drawing. After the covering has been secured over all of the pins, the pins are removed one at a time and replaced as removed with permanent securing screws.

Variations may be made without departing from the scope of the invention as it is defined by the following claims.

I claim:

1. A gripping and pulling tool for applying a covering of sheet material to a surface, said tool comprising a tubular body having a longitudinal open notch at an end thereof to receive a margin of a covering, a wall of said body adjacent the notch having a stationary jaw, a moveable jaw mounted in said tubular body, toggle means between said moveable jaw and a wall of said body opposite said fixed jaw, a handle at the end of said body opposite said notch for manipulating said body, and means comprising an element extending through said tubular body from a region adjacent said handle for moving said toggle means to clamp said jaws upon a margin of the covering, said toggle means comprising a pair of moving struts engaging said moveable jaw

and said tubular body respectively at opposite sides of said element of the toggle adjusting means.

2. A gripping and pulling tool for applying a covering of sheet material to a surface, said tool comprising a tubular body having a longitudinal open notch at an end thereof to receive a margin of a covering, a wall of said body adjacent the notch having a stationary jaw, a moveable jaw mounted in said tubular body, toggle means between said moveable jaw and a wall of said body opposite said fixed jaw, a handle at the end of said body opposite said notch for manipulating said body and means comprising a rod element extending through said tubular body from a region adjacent said handle for adjusting said toggle means to clamp said jaws upon a margin of the covering, said toggle means comprising a pair of moving struts engaging said moveable jaw and said tubular body respectively and having connection with said rod element of the toggle adjusting means at opposite sides of the latter, and said toggle adjusting means comprising a lever pivoted on said body adjacent said handle 25 and pivotally connected to said rod element.

VICTOR H. HASSELQUIST.
